UNITED STATES PATENT OFFICE.

CORWILL JACKSON, OF CHICAGO, ILLINOIS.

TAMPING OR BALLASTING MACHINE.

Application filed July 25, 1924. Serial No. 728,098.

To all whom it may concern:

Be it known that I, CORWILL JACKSON, a citizen of the United States, residing at Chicago, county of Cook, State of Illinois, have invented certain new and useful Improvements in Tamping or Ballasting Machines, of which the following is a specification.

This invention relates to improvements in tamping or ballasting machines.

The main objects of this invention are:

First, to provide an improved tamping or ballasting machine which is of large capacity.

Second, to provide an improved tamping or ballasting machine which is highly efficient in the character of work performed.

Third, to provide an improved tamping or ballasting machine which is easily manipulated.

Fourth, to provide an improved tamping or ballasting machine which is economical in structure and at the same time strong and durable.

Objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawings forming a part of this application, in which:

Fig. I is a side elevation of a structure embodying the features of my invention, the machine being shown in operative position on a railway track.

Fig. II is a front elevation, parts being broken away for convenience in illustration.

Fig. III is a detail vertical section on a line corresponding to line 3-3 of Fig. II, taken looking in the direction of the arrows.

In the drawing, the same numerals of reference indicate similar parts in all of the views.

Referring to the drawing, 1 represents a truck or car adapted to travel on a railway track, the ties of the track being indicated at 2, the rails at 3 and the road bed or ballasting material at 4. A motor is conventionally shown at 5.

Upon the truck I mount a swinging frame 6, the frame being pivoted at 7 and adjustably supported by means of the cable 8 passing over a pulley 9 on the frame 10 to a windlass 11.

I provide a crosshead 12 having arms 13 pivoted at the outer end of the swinging frame 6 at 14. This crosshead has recesses 15 in its under side adapted to receive the rails 3. The crosshead is provided with vibrating means which in the structure illustrated consists of the shaft 16 having the unbalancing weights 17 thereon. This shaft is driven by the belt 18 from the pulley 19 on the shaft 14 constituting the pivot for the crosshead. A second pulley 20 is connected by the belt 21 to the motor.

The blades or tampers 22 are pivoted at 23 on the lower edge of the crosshead, the blades being arranged in coacting pairs and their lower ends being outwardly directed or diverged as shown in Fig. I. These blades have end faces 24 of substantial width with longitudinal ribs 25 at the bottom of the faces, thus providing for a substantial end thrust on the material engaged by the blades.

When the crosshead is in elevated position the blades or tampers hang side by side but when the crosshead moves downwardly and the blades engage the material to be tamped, the material tends to separate them, thereby carrying the material under the ties. The crosshead is at the same time vibrated so that the tampers are subjected to a series of impacts, which are very effective in driving, compacting and forcing the ballasting material below the ties.

My improved tamping machine is of large capacity and is very efficient. I have illustrated an embodiment of my improvements which is very practical. I have not attempted to illustrate various modifications and adaptations which I contemplate as I believe the disclosure made will enable the embodiment or adaptations as may be desired.

Having thus described my invention what I claim as new and desire to secure by Letters Patent, is:

1. In a machine of the class described, the combination of a truck adapted to travel upon the track to be ballasted, a swinging frame carried by said truck, a crosshead pivotally mounted on said frame, a vibrating means for said crosshead, tampers

- mounted on said crosshead, and means for raising and lowering said frame. 60
2. In a machine of the class described, the combination of a truck adapted to travel upon the track to be ballasted, a vertically movable frame, a crosshead pivotally mounted on said frame, a vibrating member rotatably mounted on said crosshead, tampers mounted on said crosshead, means for driving said vibrating member, and means for raising and lowering said frame. 65
3. In a machine of the class described, the combination of a truck adapted to travel upon the track to be ballasted, a swinging frame carried by said truck, means for raising and lowering said frame, a cross head pivotally mounted on said frame, tampers carried by said crosshead, a shaft on said crosshead provided with an unbalancing weight, and means for driving said shaft. 70
4. In a machine of the class described, the combination of a vertically movable crosshead, a shaft rotatably mounted thereon and provided with an unbalancing weight, tampers mounted on said crosshead, and means for driving said shaft. 75
5. In a machine of the class described, the combination of a pivotally mounted crosshead, a vibrating means for said crosshead, and tampers mounted on said crosshead. 80
6. In a machine of the class described, the combination of a vertically movable crosshead, means for raising and lowering said crosshead, a vibrating means for said crosshead, and tampers pivotally mounted on said crosshead in coacting pairs, the ends of said tampers being laterally directed whereby they tend to separate on contacting with the material to be tamped. 85
7. In a machine of the class described, the combination of a vertically movable crosshead, means for raising and lowering said crosshead, a vibrating means for said crosshead, and tampers mounted on said crosshead. 90
8. In a machine of the class described, the combination of a head member, means for vibrating said head member, and tampers mounted on said head member in coacting pairs to receive the vibrations thereof, the pairs of tampers being disposed to receive a rail of a railway track between them and being mounted so that they tend to separate upon coming into contact with the material tamped. 95
9. In a machine of the class described, the combination of a head member, means for vibrating said head member, and tampers mounted on said head member in coacting pairs to receive the vibrations thereof so that they tend to separate upon coming into contact with the material tamped. 100
10. In a machine of the class described, the combination of a head member, means for vibrating said head member, and a pair of tampers pivotally mounted on said head member, the ends of said tampers being curved outwardly. 105
11. In a machine of the class described, the combination of a head member, means for vibrating said head member, and a pair of tampers mounted on said head member to receive the impact thereof and so that they tend to separate upon contacting with the material tamped. 110
12. In a machine of the class described, the combination of a head member, means for vibrating said head member, means for raising and lowering said head member, and tampers pivotally mounted on said head member in downwardly diverging pairs to receive the vibrations thereof. 115
13. In a machine of the class described, the combination of a head member, means for vibrating said head member, and tampers pivotally mounted on said head member in downwardly diverging pairs to receive the vibrations thereof. 120
14. In a machine of the class described, the combination of a head member, tampers pivotally mounted on said head member in coacting pairs to pass between a pair of adjacent ties, the ends of said tampers being disposed in diverging relation, and means for vibrating said head member. 125
15. In a machine of the class described, the combination of a head member, tampers pivotally mounted on said head member back to back, the ends of said tampers being curved outwardly and having their faces of substantial width with longitudinal ribs at the lower edges thereof. 130
16. In a machine of the class described, the combination of a head member, tampers pivotally mounted on said head member in coacting pairs, the ends of said head members being outwardly directed so that they tend to separate on coming into engagement with the material to be tamped, the end faces of said tampers being of substantial area, and means for vibrating said head member. 135

In witness whereof I have hereunto set my hand. 140

CORWILL JACKSON. [L. S.]
